US00D945385S

(12) **United States Design Patent** (10) **Patent No.:** **US D945,385 S**
(45) **Date of Patent:** **** Mar. 8, 2022**

(54) **PORTABLE TERMINAL**

(71) Applicant: **KYOCERA Corporation**, Kyoto (JP)

(72) Inventor: **Yusuke Takahashi**, Yokohama (JP)

(73) Assignee: **KYOCERA CORPORATION**, Kyoto (JP)

(**) Term: **15 Years**

(21) Appl. No.: **29/707,074**

(22) Filed: **Sep. 25, 2019**

(30) **Foreign Application Priority Data**

Mar. 25, 2019 (JP) 2019-006242

(51) **LOC (13) Cl.** **14-03**

(52) **U.S. Cl.**

(57) **CLAIM**

The ornamental design for a portable terminal, as shown and described.

DESCRIPTION

FIG. 1 is a front view of a portable terminal bearing the design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a top-front-right perspective view thereof;

FIG. 8 is a top-rear-left perspective view thereof;

FIG. 9 is an enlarged view of a portion of the portable terminal shown in rectangle 9 of FIG. 1; and,

FIG. 10 is an enlarged view of a portion of the portable terminal shown in rectangle 10 of FIG. 3.

The broken lines encircling portions of the claimed design that are illustrated in the enlargements form no part of the claimed design. The remaining broken lines shown in the drawings depict portions of the portable terminal that form no part of the claimed design.

1 Claim, 6 Drawing Sheets
